UNITED STATES PATENT OFFICE.

FREDERICK W. MOORE, OF NEWARK, NEW JERSEY, ASSIGNOR TO THE LUXEMOOR LEATHER COMPANY, OF NEWARK, NEW JERSEY, A CORPORATION

EMBOSSING FIBROUS MATERIAL.

1,005,059.

Specification of Letters Patent

Patented Oct. 3, 1911.

Application filed August 8, 1909. Serial No. 511,957.

To all whom it may concern:

I, David W. Moore, a citizen of the United States, residing in Newark, county of Essex, and State of New Jersey, have invented an Improvement in Embossed Fibrous Material, of which the following description, in connection with the accompanying drawings, is a specification, the letters *a* on the drawings representing

like parts.

This invention relates to a layer or sheet of felt or other fibrous material having one or both of its surfaces of a finer or firmer texture or quality than the intermediate or body portion of said layer or sheet, and has for its object to provide one of the finer or firmer surfaces with a design, which is formed by the removal of parts of said finer or firmer surface and not of the coarser body portion, whereby a superior product is obtained in which the design is sharply defined and the detail of the same made to stand out prominently. This result may be accomplished by subjecting the sheet or layer of felt to compression, so that parts of one of its finer or firmer surfaces are molded into formations in design projected beyond the remaining portions of said surface a distance sufficient to enable said projecting parts to be removed yet not to such extent as to remove all of the finer or firmer surface, whereby the design is formed entirely in the surface of finer or firmer nature or quality, and as a result, the detail of the design is made to stand out prominently and sharply, and a superior product is obtained, which is not weakened but retains substantially the strength of the original sheet or layer, thereby enabling the felt or other fibrous layer or sheet having the design thereon to be used not only for decorative or ornamental purpose, but also used for manufacturing purposes, such as for slippers, boots and shoes, bags, etc., inasmuch as the sheet or layer with the design thereon is not liable to be torn, split, stretched or otherwise injured in manipulating it to adapt it to the particular work.

The sheet or layer of felt or other fibrous material may have the surface layer of finer or firmer material in which the design is formed of two distinct colors, one of which penetrates the finer or firmer material but partially its depth, while the remaining or underlying portion of the finer or firmer

material is of a distinctive color and may be of the same color as the body portion of the sheet or layer, which also serves to emphasize the appearance of the design.

The design may and preferably will be formed by means of the apparatus herein shown and which will be hereinafter described.

Figure 1 represents one form of apparatus with which my improved product may be produced. Fig. 2, a plan of a sheet or layer of fibrous material embodying this invention. Figs. 3, 4, and 5, details in section on an enlarged scale to be referred to, and Fig. 6, a plan of a sheet or layer with a different design from that shown in Fig. 2.

Referring to the drawings, *a*, Fig. 2, represents a sheet or layer of felt or other fibrous material, and *b* represents the design formed in one of its surfaces.

The design *b* shown in Fig. 2, consists of a series of parallel grooves, which are formed by removing parallel strips or portions from one surface of the sheet or layer, which may be effected by the apparatus represented in Fig. 1.

The apparatus shown in Fig. 1, comprises essentially a bed roll *c* of hard rubber, steel or other substantially hard material, which supports and rotates a roll *d* having engraved or otherwise formed on its circumference the design to be formed in the sheet or layer *a*. The roll *d* may be designated the pattern roll and has co-operating with it a gage roll *f* and pressure roll *g*. The sheet or layer *a* without the design thereon is designed to be fed between the gage roll *f* and the pattern roll *d* and to be compressed between the same, so that a portion of one surface of the sheet or layer *a*, herein shown as the lower surface is forced into the recesses, which form the design in the pattern roll, and which are represented by dotted lines in Fig. 1 as irregular grooves 10 arranged parallel to one another.

The gage and pattern rolls have cooperating with them a knife 12, preferably a belt knife, whose cutting edge is extended to near the vertical line passing through the center of the said rolls and substantially tangent to the circumference of the pattern roll, so as to remove only those portions of the under surface of the sheet or layer, which are projected into the recesses 10, and thereby form in the under surface of the

fibrous sheet or layer the design *b* corresponding to the recesses 10 in the pattern roll.

Sheets or layers of fibrous material have one or both of their outer surfaces of a different texture or firmness than the intermediate or body portion, which exists not only in manufactured sheets or layers of fibrous material, such as felt, but also in natural fibrous sheets or layers, such as skins, and this condition is represented in Figs. 3, 4 and 5, in which 20 represents one outer surface of fine or firm material or texture; 21, the other, and 22 the intermediate or body portion of coarser texture or material. In order to obtain a sheet or layer of fibrous material having a design formed on one of its surfaces, which is serviceable for commercial as well as ornamental uses, and which when subjected to strain will not split, tear apart or stretch to such extent as to destroy or impair the design and render the article unfit for use, the design is formed by removing only a portion of the firmer outer material, as for instance the fine material of the surface 20. To this end, the cut made by the knife does not extend into the coarser material comprising the body portion, but is regulated so as to extend but partially through the firmer material comprising the surface 20. This result is effected with the apparatus herein shown by making the recesses 10 of a depth less than the thickness of the finer or firmer material comprising the outer surface 20, and arranging the knife 12, so that its cutting edge is tangential to the outer circumference of the pattern roll, so that only the portions of the outer surface 20, which are projected into the recesses and are confined therein against lateral movement by the walls of the recesses will be cut by the said knife, and as a result the strength of the sheet or layer is not materially impaired as the cut does not extend through the strong finer or firmer material. This is clearly represented in Fig. 4, wherein it will be seen that the groove or channel *b* extends but partially through the finer or firmer material comprising the outer surface 20. The walls of the cavity formed in the sheet or layer of fibrous material are substantially perpendicular to the surface of the sheet or layer, whereby the detail of the design formed by the removed portion of the surface is brought out sharply and a superior product is obtained. The same thing is true when the sheet or layer is a skin, which is represented in Figs. 5 and 6, and which is provided with a design 25 similar to a leaf. The design 25 may be made in the grain side 30 of the skin, which may

correspond to the surface 20 of the felt layer *a*, or it may be made in the flesh side 31 corresponding to the surface 21 of the felt layer. The grain and flesh sides or surfaces of the skin are materially firmer in texture than the intermediate body portion or pith 32, represented in Fig. 5.

The apparatus may be provided with a means for removing fine cut portions from the recesses in the roll *d*, said means being shown as a revoluble brush 40.

In practice, the surface of the felt, which is to be provided with the design, may be dyed or colored with a different color for a portion of its depth as, for instance, black, while the remaining portion of said surface may be colored the same as the body portion, as for instance, red, and the same is true of the skin. This contrast in color serves to enhance the value of the product.

Claims.

1. As an improved article of manufacture, a flexible sheet or layer of fibrous material having an outer surface of a firmer texture than the body portion of the same, and having portions of said firmer surface removed to form a design in the said outer surface, the walls of the portion in design being substantially perpendicular to the said surface and the portions removed extending toward but not into said body portion, whereby the design is sharply defined without materially impairing the strength of the said outer surface, substantially as described.

2. As an improved article of manufacture, a flexible sheet or layer of fibrous material having an outer surface of a firmer texture than the body portion of the same, and of a color which is distinguishable from that of the body portion and having portions of said firmer surface removed to form a design in the outer surface of a color which is distinctive from the color of the outer surface, the walls of the portion in design being substantially perpendicular to the said surface, substantially as described.

3. As an improved article of manufacture, a flexible sheet or layer of felt having one of its outer surfaces of a different color than its body portion and having portions of said outer surface removed to form a surface in design of different colors, the walls of the portion in design being substantially perpendicular to said surface.

In testimony whereof, I have signed my name to this specification in the presence of two subscribing witnesses.

FREDERICK W. MOORE.
